UNITED STATES PATENT OFFICE.

EMILE ILG, OF BROOKLYN, NEW YORK.

SEWING-MACHINE.

SPECIFICATION forming part of Letters Patent No. 723,278, dated March 24, 1903.

Application filed April 26, 1902. Serial No. 104,806. (No model.)

To all whom it may concern:

Be it known that I, EMILE ILG, a citizen of the United States, residing in the borough of Brooklyn, city, county, and State of New York, have invented certain new and useful Improvements in Sewing-Machines, of which the following is a specification.

My invention relates to sewing-machines, and particularly to that type of sewing-machine employed for sewing goods together arranged at an angle.

My invention is particularly adapted for sewing the edges and corners of satchels and other like articles.

I will describe a sewing-machine embodying my invention and then point out the novel features thereof in a claim.

In the accompanying drawings, Figure 1 is a view, partly in side elevation and partly in vertical section, of a sewing-machine embodying my invention. Fig. 2 is a detail elevational view with the front plate of the bed removed.

Similar letters of reference designate corresponding parts in both figures.

The sewing-machine head is shown as consisting of a bed A' and an arm A² of ordinary construction. The bed A' is here shown as being substantially in the form of a hollow cylinder to accommodate the driving-shaft employed for operating a shuttle mechanism A³, located in a recess provided in the end of the arm.

A⁴ designates a throat-plate which is located, as usual, over the shuttle mechanism and is provided with the usual opening a for a needle to pass through to coat with the shuttle mechanism in forming stitches, and with an opening a', through which a lower feed-dog A⁵ extends and works. The usual mechanism is provided for moving the feed-dog to feed the material. As shown, the lower feed-dog is in the rear of the needle-opening and is located close to the end of the arm.

A⁶ designates an inclined surface provided at the end of the bed A' and in front of the shuttle mechanism, and A⁷ designates a plate located below the inclined surface A⁶ and secured to the bed A' in front of the shuttle mechanism. The inclined surface A⁶ is here shown as consisting of a plate.

B designates a needle-bar carrying a nee-

dle b and having the usual vertical reciprocation. The means for producing its reciprocation may be of any suitable character in 55 the art, and hence I shall not further describe or illustrate any.

C designates an upper feed-dog which also has the function of pressing or holding the material onto the lower feed-dog and also assisting in the feed of the material. It is here shown as being in the form of a disk, which is rotatively mounted and provided with a beveled and knurled edge c'. Any well-known mechanism may be employed for raising and 65 lowering the upper feed-dog.

It will be seen from the drawings that the needle is reciprocated in front of the feeding mechanism and that both the needle and feeding mechanism are located close to the 70 edge of the bed in order that material arranged at an angle, as illustrated in dotted lines, may be sewed. It will also be observed that the material on which the feed mechanism acts is waste, and hence above the 75 abjectionable marking of the feed mechanism on the goods which is common in other machines. It will also be seen that according to my invention there are incasing members for the lower stitch-forming mechanism, said 80 members being provided with an upper face or throat-plate through which the needle and feed mechanisms operate and with an end face approximately upright and an intermediate inclined surface lying at an angle with 85 both of said faces and extending into close proximity to the needle-hole. According to this construction seams may be formed close to the bends or angles of leather goods and other stiff materials to be stitched.

Obviously some features of my invention may be used without others, and my invention may be embodied in widely-varying forms.

Therefore, without limiting myself to the construction shown and described nor enumerating equivalents, I claim, and desire to obtain by Letters Patent, the following:

In a sewing-machine, the combination with a tubular bed, of a throat-plate secured to the upper surface of the bed and having an 100 opening for the passage of a needle in close proximity to its outer end, a reciprocating needle to work through said hole, a shuttle mechanism supported in the tubular bed

to coöperate with the needle to form stitches, said shuttle mechanism extending beyond the front end of the throat-plate, and a plate to close the front end of the tubular bed, said plate having an inwardly-inclined upper portion, the upper edge of which abuts the front edge of the throat-plate, substantially as and for the purpose specified.

In testimony whereof I have signed my name to this specification in the presence of 10 two subscribing witnesses.

EMILE ILG.
